Attala
Atty.

UNITED STATES PATENT OFFICE.

JOHN EDWARD THOMPSON, OF PAISLEY, ONTARIO, CANADA.

AEROPLANE-PROPELLER.

1,332,528.

Specification of Letters Patent.

Patented Mar. 2, 1920.

Application filed December 7, 1918. Serial No. 265,741.

To all whom it may concern:

Be it known that I, JOHN EDWARD THOMPSON, of the town of Paisley, in the county of Bruce, in the Province of Ontario, Canada, have invented certain new and useful Improvements in Aeroplane-Propellers, of which the following is the specification.

My invention relates to improvements in aeroplane propellers and the object of the invention is to provide simple means for changing the angle of the propeller blades to increase or decrease the draw, in which means are provided for so coupling the blades together to overcome the strain due to centrifugal force as the propeller revolves, in which means are provided for indicating to the airman the angle at which the blades are set and it consists essentially 20 of the following arrangement and construction of parts as hereinafter more particularly explained.

Figure 1, is a sectional perspective view of my device together with the butt ends. 25 of the propeller blades.

Fig. 2, is a sectional detail showing the means for connecting the butt ends of the propeller blades together.

Fig. 3, is a front elevation of the device 30 whereby the blade setting device is thrown into operation.

In the drawings like characters of reference indicate corresponding parts in the various figures.

1 indicates the propeller shaft mounted in a suitable bearing 1^x carried by an aeroplane. 2 indicates a controlling shaft mounted in suitable bearings 2^x and 2°, on one end of which is mounted a controlling 40 lever 3 and at the opposite end is secured a sprocket pinion 4. 5 indicates a supplemental shaft also mounted in bearings 1^x and provided at one end with a sprocket wheel 5^x connected by a sprocket chain 5° 45 to the sprocket wheel 4 and at the opposite end with an eccentric 5°.

1° indicate vertical guide ribs which are formed on the outer end face of the bearing 1^x. 6 indicates a vertically slideable member held between the guide ribs 1° and provided with friction contact ribs 6^x and 6° which are concentric to the center of the propeller shaft when in their operative position. The member 6 is provided with a depending

tongue 6' in which is formed a circular orifice 6° in which fits the eccentric 5°. 7 indicates a circular housing which is secured at 7^x to the outer end of the propeller shaft 1. The housing 7 is in the form of a hollow circular drum provided at diametrically opposite points in its periphery with tapered bearings 7' and 7° which are provided with inner and outer ball races 7° and 7°.

8 and 9 indicate the inner ends of the propeller blades, the butt ends 8^x and 9^x of which are connected together by a suitable connector 10. The connector 10 is formed preferably by a central sleeve 10^x, the outer edges 10° and 10^x of which are formed inclined to form one side of a ball race.

11 and 12 indicate cylindrical members secured at their inner ends to the member 10^x, each member 11 and 12 being provided with an inner ball race member 11^x and an outer ball race member 11°. The butts 8^x and 9^x are provided with corresponding ball races 8° and 9° in which fit balls 8' and 9'. By this means the butt ends of the blades are secured firmly together and yet are free to revolve independently one of the other. 13 indicates a worm gear secured to the butt end of the blade 8 and 14 indicates a worm gear secured to the butt end 85 of the blade 9.

15 and 16 indicate shafts journaled in the walls of the housing 7 and provided with worms 17 and 18 meshing with the worm gears 13 and 14. 19 indicates a shrouded sprocket secured to the shaft 15 90 and 20 indicates a shrouded sprocket secured to the shaft 16, the sprockets 19 and 20 being connected together by a sprocket chain 21. 22 indicates a friction wheel secured to the inwardly extended end of the shaft 15 so as to be brought alternately into engagement with the ribs 6^x and 6° as the member 6 is adjusted vertically either in one direction or the other.

It will be understood that the engine 100 shaft 1 and the housing 7 carried thereby with the blades 8 and 9 mounted therein revolve continuously when the engine is driven and that when it is necessary to adjust the blades in one direction the lever 3 is thrown over so as to turn the shafts 2 and 5 and the eccentric 5° in such a direction as to draw the member 6 down and the

inner periphery of the rib 6^x into contact with the friction wheel 22. As the propeller revolves the friction wheel 22 contacts with the rib 6^x for a small portion of its travel revolving the worm 8^x and worm gear 13 and propeller blade 8 and simultaneously through the sprocket 21, sprocket 20, shaft 16 and worm 18 and worm gear 9^x revolving the propeller blade 9 in the opposite direction. It will be understood that the worms 17 and 18 are set in opposite directions one to the other and, therefore, the blades 8 and 9 set in a corresponding direction.

15 When it is necessary to set the blades in the reverse direction the lever 3 is thrown in the opposite direction so as to turn the shafts 2 and 5 and the eccentric 5' to carry the member 6 upwardly and the upper face 20 of the rib 6^x into engagement with the friction wheel 22 thereby setting the mechanism in the opposite direction.

25 In order to indicate to the airman the angle at which the blades are set I have provided the following device:

20 23 indicates a ring which is mounted on studs 24 and 25 extending through the back wall of the housing 7, the ring 23 being located within the housing and spring held 30 away from the inner face of the wall of the housing by compression springs 25^x. 26 and 27 indicate collars carried upon the inner ends of the blades 8 and 9 and provided with friction rollers 26^x and 27^x against which 35 the ring 23 is normally held by the compression springs 25^x. 28 indicates a ring located to the outside of the rear wall of the housing 7 and secured to the opposite ends of the studs 24 and 25. 29 indicates a rod 40 which may be supported in suitable bearings so as to slide longitudinally. The outer end of the rod 29 is provided with a depending fork 29^x in which are located ball bearings 29' and 29^x bearing against the opposite 45 site faces of the ring 28.

50 30 indicates an indicating pointer swingably mounted on an indicating plate 31 and provided with an arm 32, to the outer end of which the opposite end of the rod 29 is secured.

55 It will be seen that when the propeller blades are turned in one direction they will force the ring 23 toward the wall of the housing 7 against the compression of the springs 25 thereby forcing the rod 29 longitudinally to move the pointer. When the 60 blades are set in the opposite direction the rollers 26^x and 27^x are carried away from the ring 23 and the ring is carried away from the wall of the housing 7 by the compression springs drawing the rod 29 in the opposite direction.

65 It will, of course, be understood that the propeller blades and housing 7 are continually revolving and that the ring 28 en-

gaging the rod 29 revolves between the roller bearings 29' and 29^x during the operation.

From this description it will be seen that I have devised a very simple construction 70 in which the blades of the aeroplane propeller may be set to any angle desired and yet are so connected together that there is no danger of their being carried apart by reason of the great tangential strain produced by the revolving parts. 75

It may be understood that mechanisms have already been devised whereby the propeller blades may be set to any desired angle 80 but the difficulty has been that by such construction the blades necessarily are divided one from the other and mounted in separate bearings. Heretofore it has been found impossible to devise a structure sufficiently strong to overcome the great strain due to 85 the tangential force created by the propellers revolving at high speed and it is to overcome this defect and to thereby make possible the use of mechanism whereby the propeller blades may be set to any desired 90 angle to produce any required draw that I have devised the foregoing mechanism.

What I claim as my invention is:

1. In an aeroplane propeller, a bearing member adapted to be secured to the end 95 of the propeller shaft, propeller blades journaled in the bearing member in proximity to their butt ends, means for connecting the butt ends of the blades together so that they have independent movement, a worm gear 100 mounted upon the butt of each propeller blade, supplemental shafts carried by the bearing member having oppositely set worms engaging the gears, and means operated by the airman for simultaneously turning the worm shafts in either direction. 105

2. In an aeroplane propeller, a bearing member adapted to be secured to the end of the propeller shaft, propeller blades journaled in the bearing member in proximity 110 to their butt ends, means for connecting the butt ends of the blades together so that they have independent movement, a worm gear mounted upon the butt of each propeller blade, supplemental shafts carried by 115 the bearing member having oppositely set worms engaging the gears, a sprocket gear connection between the worm shafts, a friction gear mounted upon one of the worm shafts, friction members provided with 120 faces substantially concentric to the center of the worm shaft, and means operated by the airman for drawing such faces alternately into engagement with the friction gear. 125

3. In an aeroplane propeller, a bearing member adapted to be mounted on the propeller shaft, propeller blades independently mounted in the bearing member, means operated by the airman for adjusting the 130

angular set of the propeller blades, a cam member mounted upon each propeller blade, a ring spring held in contact with the cam members, studs mounted in the bearing member carrying such ring member, an exterior ring member carried by the opposite ends of the studs, a longitudinally movable rod having a fork at one end engaging the

outer peripheral portion of the outer ring member, a pivoted pointer, and an arm extending therefrom to which the opposite end of the rod is pivotally connected.

JOHN EDWARD THOMPSON.
